CAKE INSERTER

Eugene Leslie Davis, Jr., Beach, and Maurice Edward Kalen, Richmond, Va., assignors to E. I. du Pont de Nemours & Company, Wilmington, Del., a corporation of Delaware

Application April 28, 1950, Serial No. 158,674

1 Claim. (Cl. 29—234)

1

This invention relates to apparatus for placing expandable inserts in bucket cakes of rayon.

Since almost the beginning of the bucket spinning process of making rayon yarn, bucket cakes have been inserted either before washing and liquid processing or after drying and before unwinding. The expandable inserts used have been squeezed together by hand, placed inside the cake annulus and released to their expanded position, thereby pressing against the inner wall of the cake and supporting it. Over the years, the size of the spin cake has increased from a matter of about one-half pound to three pounds or more of dry yarn, and the wet acid cakes are of the order of three or four times these weights. To support a large acid cake satisfactorily, the insert must be quite stiff, and collapsing these larger, stiffer inserts by hand and hand-inserting them in the cake has brought about a great deal of yarn damage and loss, or degradation, of production. It has, therefore, been considered desirable to provide mechanical means for placing the collapsed insert inside the cake so as to avoid sliding it across the inner yarn windings.

It is, therefore, an object of this invention to provide a device for inserting an expandable insert into a cake of rayon without disturbing the inner windings of yarn and of sufficient stiffness to retain the inner windings of yarn in their places. Other objects will be apparent from the description that follows.

These objects are accomplished by an inserter comprising a collapser which compresses the support to be inserted into a package and an inserting tube which draws the collapsed support from the collapser into the core or cavity of the package and releases it there. The insert then automatically expands in the cavity and supports the inner wall of the package.

The invention will be more clearly understood by reference to the following figures, given for illustrative purposes only and of which

Figure 1 is a side view of the device of this invention portably mounted;

Figure 2 is an end view taken on line 2—2 of Figure 1 showing the jaws of the collapser open;

Figure 3 is taken on line 3—3 of Figure 1;

Figure 4 is taken on line 4—4 of Figure 1;

Figure 5 is a sectional side view of the inserting tube which has passed through the cake and over the insert;

Figure 6 is a view similar to Figure 5 but showing the inserting tube in position to release the insert within the cavity;

2

Figure 7 shows the insert properly set in and Figure 8 is taken on lines 8—8 of Figure 5 to show the snubber.

Referring to Figure 1, the insert 1 is normally a perforated, expendable metal sheet, having a shape conforming to that of the core of the package 2 to be supported. The insert 1 is placed in the collapsing fingers 3 of collapser 4 and the cake 2 to be inserted is placed in the saddle 5. The electric button 6 is then pressed to actuate the solenoid 7. This solenoid then trips the single revolution clutch 8, so that the shaft 25 makes one complete revolution and stops. During this revolution the cams 9 close the collapsing fingers 3 and the gear 10 turns the gear 11, moving the arm 12 downward and pulling the tube 13 forward. The inserting head 14, driven by cable 36, slides over the insert 1 just before the cams 9 cause the collapsing fingers to open. When the fingers have opened, arm 12 moves back to an upward vertical position influenced by weight 15 due to the fact that teeth have been removed from a portion of gear 10 to cause the gears to lose contact and leave gear 11 free to turn. The head 14 is then simultaneously withdrawn to original position by weight 15 and the insert is extracted by the impact of extractor rod 16 against a stop 17. The cycle is now complete. Two fingers, 37 and 38, respectively are located on gears 10 and 11 to cause the gears to re-mesh at the start of a new cycle. The motor 19 drives through a speed reducer 20 to a slip clutch at 21. The entire device may be mounted, if desired, on a truck 22.

The collapsing part of the mechanism is shown in further detail in Figure 2. This shows an end view of fingers 3 and cams 9. The dotted lines 23 and 24 indicate the fingers and insert, respectively, in the closed or collapsed position. This position is shown also in Figure 8. The cams 9 are fastened to the shaft 25 to synchronize with the other mechanism actuating the inserting tube 13 and rod 16. The cams 9 are rotated counter-clockwise, one full revolution for each inserting cycle. The cam followers 26 mounted at one end of pivotable arms 27 on fixed pivots 28 are connected with linkages 29 to form a parallelogram hook-up. This causes the collapsing fingers to move substantially in a horizontal direction toward and away from the center of the insert, thereby causing the insert to collapse or expand, respectively.

In Figure 3 is shown in detail the clutch 8 and solenoid mechanism which puts into operation the rotation of shaft 25 and the movements of

cams 9 and other synchronized parts. With reference to this drawing, reference numeral 8 refers to a single-revolution clutch. Power is applied to the clutch by means of a sprocket 30 (shown in Figure 1) keyed to an extended bronze bushed sleeve 31 which is free to rotate around shaft 25, the sprocket being driven by chain 32 from sprocket 18 fastened to the output shaft of the gear reducer 20 which in turn is connected to motor 19. This driving member of clutch 8 rotates continuously on shaft 25. The other part of the clutch 8, which carries the trip mechanism, is keyed to shaft 25. Solenoid 7 is attached to the trip lever 33, which rides in a step in a cam on clutch 8. When in the position shown, the driven part of clutch 8 does not rotate and shaft 25 is stationary. When solenoid 7 is instantaneously activated by switch 6, the trip lever 33 is withdrawn from the step toward solenoid 7 and spring 34 snaps the clutch parts into driving position (for instance, by bringing about a wedging engagement between the part of the clutch keyed to shaft 25 and the revolving sleeve 31 part of the clutch). As the clutch rotates driving shaft 25, the trip lever 33 is pulled back against the cam on the clutch by spring 35 and when the step comes around to the trip lever 33 again, the driven part of the clutch comes to rest. Therefore, while the motor, speed reducer, and chain drive through the sprocket run continuously, the shaft 25 makes just one revolution when switch 6 is pressed.

As shown in Figure 4, when the machine is at rest, the cable 36 holds gear 11 in a position so that arm 12 is straight up. Gear 10 is keyed to shaft 25 in such a position that when the machine is at rest, the two gears are out of mesh, due to the fact that one-third of the teeth are removed from gear 10. When switch 6 is pressed and shaft 25 begins to rotate, the finger 37 on gear 10 strikes the steel pin 38 on arm 12 and positively meshes the teeth on the two gears. As gear 11 rotates, arm 12 pulls the tube 13 forward by means of the cable 36. The tube 13 completes its forward travel when arm 12 has rotated approximately 160°. The remainder of the vertical travel of the end of arm 12 is taken up by a spring 39 attached to the cable. When arm 12 has rotated approximately 200°, gear 11 contacts the position on gear 10 where the teeth have been removed. Arm 12 is then freely pulled by weight 15 into the upright position and tube 13 is pulled back to the position shown in Figure 1.

In Figure 5 is shown the sub-assembly of the inserting tube 13. The inserting head 14 and tube 13 move forward through the cake 2 for a total distance of about 13 inches. In about 11 inches of travel, the inserting head 14 meets the collapsed insert 1. The insert 1 slides into the inserting head 14 and pushes the extractor head 39 and rod 16 back about 2 inches. The machine is synchronized by the position of cams 9 relative to gear 10 on shaft 25 so that the fingers 3 release the insert just before inserting head 14 begins to travel back through the cake with the collapsed insert, as shown in Figure 6. The collapsed insert is small enough so as not to disturb the inside yarn windings of the cake. When the assembly nears the end of the backward travel as shown in Figure 7, the extractor rod 16 hits stop 17 with sufficient impact for extractor head 39 to force the insert 1

out of the inserting head 14. The insert 1 immediately expands.

The insert snubber 40 is shown in Figure 8. When the insert 1 is ejected from the inserting head 14, it often tends to jump back through the cake. The snubber 40 serves to grab the insert between its rubber-lined jaws 41 and limit the undesirable horizontal movement of the insert, while still allowing the insert to expand. 10 This action prevents disarrangement of the inside threads in the cake and allows more cake-to-cake uniformity of placing the insert therein. The jaws are pivoted as shown at 42 and are held together for snubbing action by an expandable band 43. The inserting tube 13 is suitably supported in any convenient manner, as for example, by support 44 shown in Figure 1. Collar 45 is attached to cable 36 and forces the head to move backwards or forwards depending upon the cable movement.

Synchronizing the machine is most important and is accomplished by correct positioning of the cams 9 and gear 10 with respect to the clutch 8. The speed reduction from driving motor 19 through the gear reducer 20 is 84 to 1. The speed is then increased through the chain drive at a ratio of 3 to 2. The complete inserting cycle for the machine is approximately 2 seconds.

By means of this machine, large bucket cakes 30 of the order of 3 lbs. to 5 lbs. (dry weight basis) can be easily inserted with heavy gauge resilient but stiff perforated inserts that will expand effectively against the inner wall of the cake and retain the inside layers of yarn in place during centrifugal washing and/or other processing steps. The uniformity and quality of yarn production is greatly improved while the cost of inserting and handling wet acid cakes of viscose rayon is noticeably reduced.

40 It is, of course, possible to use parts other than those described above which will operate in the same or similar fashion. For example, it is possible to make and use effectively a hand operated machine, if desired. It is also possible 45 to use an inserting head that fits over the compressed support at the wider end than is shown. The support contained in such a head may then be inserted or pushed, by hand or mechanically into the cavity from the larger opening of the package. The automatic device described herein 50 is preferred for its greater efficiency. The package may be of any size or shape and the insert may likewise vary. Articles other than yarn, such as ribbons, films, etc., may, of course, be carried or supported in the package.

55 Any departure from the above description which conforms to the present invention is intended to be included within the scope of the claim.

60 We claim:

Apparatus for inserting an expandable insert into the hollow core of a package of yarn and the like which comprises a support having a saddle for holding a package in a fixed position, an insert collapser located on said support on one side of the package with mechanism for actuating the collapser to compress the expandable insert sufficiently to fit into the core of the package, an insert holder comprising

65 an insert-engaging head on an inserting tube slidably mounted on said support on the opposite side of the package from said collapser for movement axially through the package, mechanism for moving the holder through the package to 70 engage one end of the compressed insert and

75 engage one end of the compressed insert and

pull the insert from said collapser into the package, a snubber located on said support at the end of the package opposite to said collapser and adapted to restrict horizontal movement of the insert out of the package, and an extractor rod slidably mounted in said inserting tube and adapted to engage a fixed stop on said support to disengage the insert from the holder when the insert has been positioned within the package.
